UNITED STATES PATENT OFFICE

JEFFREY J. WALLACE, OF AMITE, LOUISIANA, ASSIGNOR TO GULLETT GIN COMPANY,
OF AMITE, LOUISIANA

DOUBLE CONVEYER DISTRIBUTOR

Application filed April 16, 1931. Serial No. 530,655.

This invention relates to double-screw conveyers adapted to be used instead of the endless belt spiked conveyers in common use in distributors for cotton ginning systems.

The main object of the present invention is to provide a distributor system in which the conveyer boxes are built up in sections, the number of which is determined by the number of gins to be served, and in which the sides of the sections are shipped so that they can be readily nested for storage and shipping.

Another object of the invention is to provide a conveyer in which the sides of the boxes therefor are formed from sheet metal, having plane faces arranged at an angle to each other by operation in common bending machines.

A further object of the invention resides in the method of manufacturing the conveyer boxes in sections of standard length to correspond to the standard lengths of screw conveyers as manufactured by regular conveyer manufacturers for this purpose.

Still another object of the invention resides in making the filler pieces, designed to form the bottom of the conveyer box between discharge hoppers, of different lengths to correspond to the center-to-center distances between hoppers in ginning outfits made by various manufacturers.

Another object of the invention resides in the peculiar design of screw-hanger brackets which are not only used to journal the various screw sections in the conveyer boxes but are also used to secure the upper edges of the sides of these boxes in properly spaced apart relation.

A further object of the invention resides in the design of the discharge hoppers spaced along the distributor box and constructed so that the rate of discharge in each hopper may be varied as desired.

Other objects of the invention will become

apparent as the detailed description thereof proceeds.

In the drawings:

Figure 1 is a front elevation of the distributing system embodying the present invention;

Figure 2 is a perspective view of one side of the conveyer box of the said system, part thereof being broken away to show details of construction;

Figure 3 is a broken front elevation of one of the sections of the distributor system, having a side removed and parts thereof being shown in section to illustrate details of construction;

Figure 4 is a vertical section taken on the line 4-4 of Figure 3;

Figure 5 is a fragmentary front elevation of the left hand end of the section shown in Figure 3;

Figure 6 is a vertical transverse section on the line 6-6 of Figure 3;

Figure 7 is a perspective view of a hanger bracket used to support the shafts of the conveyer screws forming a part of this invention;

Figure 8 is a vertical section taken on the line 8-8 of Figure 7, the scale being enlarged;

Figure 9 is a perspective view of one of the filler pieces forming the bottom of the conveyer box between the discharge hoppers thereof;

Figure 10 is a fragmentary side elevation of an adjustable discharge hopper connected up to a cotton gin;

Figure 11 is a fragmentary end elevation of a linkage for controlling the operation of the valve in the discharge hopper; and

Figure 12 is a vertical section through a discharge hopper forming part of the present invention.

As shown in Figure 1 of the drawings, the system comprises a separator 1 of any well known construction and suitably connected

to one end of a conveyer distributor adapted to feed cotton from the separator and through any desired number of hoppers to a corresponding number of gin feeders. The distributor conveyer shown in the drawings is made up in three sections S, S1, S2 designed to feed cotton to the hoppers H, H1 and H2. While there are only three sections shown in the drawings it must be understood that the system may comprise any desired number of sections which correspond in number to the number of gins to be fed.

In this system each of the sections is the same in length as every other section; that is, the sections are of a standard length. The length of each section corresponds to a standard length of screw conveyers as manufactured by the various makers thereof. In the present invention each section of the conveyer box comprises side walls 2 and 3 (see Figure 6) made of sheet metal bent to the desired shape in a common bending machine. The opposite side walls 2 and 3 are identical in cross section so that it is only necessary to bend all the side walls in the same shape.

Each of the side walls of the several sections is shaped from a single sheet of material to form a central vertical part 4. The sheet is then bent at obtuse angles to form the inclined parts 5 and 6. The inner end of the part 5 is bent vertically upward to form a part 7 (see Figure 6), which in turn is bent to form the horizontal flange 8. A bar 9 of angle iron is seated in the corner formed by the part 7 and the flange 8, and is suitably riveted or otherwise secured in this position.

The lower inclined part 6 of the side wall connects with a horizontal part 10 which is turned down at its inner edge to form a vertical part 11; and this part 11 is turned outwardly to form the part 12, which is then turned up to form a stiffening flange 13. In the corner formed between the parts 10 and 11 there is suitably secured a bar of angle iron 14.

It will be apparent from the description so far that the side walls of each section are formed from sheets of material, each of which is bent to form a plurality of relatively inclined plane faces, the outer faces being bent to form stiffening flanges adapted to receive angle irons for bracing the walls lengthwise and for securing the sides to suitable members forming the top and bottom of the distributor box.

The opposite ends of the side walls of each section are connected to each other by filler members 15 (see Figure 9). Each of these filler members is made as a hollow casting having a vertical end wall 16 (see Figure 3) connected to side walls 17 and 18, having their opposite ends connected to each other by the end wall 19. The walls 17 and 18 have their upper edges connected to upwardly inclined walls 20 and 21 respectively, and these

walls 20 and 21 have their inner edges connected to the upwardly sloping walls 22 and 23, which meet in a ridge 24. The ridge 24 is intended to be substantially horizontal when in position as part of the conveyer 70 box, and meets a sloping wall 25 which extends upwardly from the upper edge of the wall 19 somewhat similarly to the sloping hip of a hip-roof.

Each of the walls 17 and 18 is provided with any desired number of apertures 26 adapted to receive bolts or rivets for securing the member 15 to the angle irons 14 which form stiffening bars for the lower ends of the side walls of each section. The vertical end wall 16 is provided with suitable bolt holes 27 adapted to receive bolts or rivets for securing the end of one filler member 15 to the similar end of a filler member in the adjacent section of the conveyer box.

The downwardly sloping walls 25 are to be positioned toward the inner part of each section so as to form hopper walls for conducting cotton to a hopper immediately below 90 each section. The walls 19 of each member 15 are provided with apertures 28 adapted to receive bolts or rivets for securing the upper end walls of the hoppers to said filling members 15 and in position to receive cotton to be 95 discharged from the distributor into the cotton gins.

The opposite ends of each side wall have the castings 29 and 30 riveted or otherwise suitably secured thereto; and each casting has 100 a flange 31 and 32 extending flush with the ends of the side wall and perpendicular to the faces thereof, the said flanges being provided with suitable apertures 33 and 34 adapted to receive bolts by which the flanges 105 of the adjacent sections are secured to each other in forming a conveyer box for a battery of gins.

As will be apparent from inspection of Figure 2 of the drawings the castings 29 and 110 30 are made in pairs, and are shaped to conform to the shape of the side walls, and thereby operate not only to secure the ends of the side walls of the several sections to each other but also serve to stiffen the walls transversely.

The left hand end of the section S has a closure plate 35 bolted to the flanges of the side walls of the said section, and this plate is provided with bearings for the drive shafts 120 of the conveyer screws 36 and 37 which are mounted in the conveyer box to rotate in opposite directions as shown in Figure 4 of the drawings. The drive shafts 38 and 39 are journaled in bearings 40, only one of 125 which is shown in the drawings, and these shafts are also journaled in suitable bearings formed in a gear case 41.

The shaft 39 extends through the gear case 41 and has a pulley 42 secured thereto to be 130

driven by any suitable driving mechanism. The shafts 38 and 39 have the gears 43 and 44 secured thereto and in mesh with each other to be driven in opposite directions, and thereby drive the conveyer screws 36 and 37 in opposite directions looking down in the conveyer box, as seen in Figure 6 of the drawings. While the conveyer screws might be designed to rotate in directions opposite to that shown in the drawings, it is preferred 10 that they do rotate as they are shown in this case, because it is essential that the cotton be carried mainly on top of the conveyer screws in order to secure the greatest efficiency in operation.

15 It is of course obvious that the closure plate 35 will be bolted to the perpendicular wall 16 of the filler member 15 which secures the bottom end of the opposite side walls in properly spaced relation to each 20 other. This construction forms a very rigid connection between the opposite wall of the section S at the driving end of the conveyer screws.

25 The screws 36 and 37 have one end of each suitably secured to their respective driving shafts 38 and 39. The other ends of the screws 36 and 37 are suitably secured to short stub shafts 45 (only one of which appears in the drawings); and these shafts are 30 journaled in bearings 46 and 47 formed in the lower ends of arms 48 and 49 respectively which depend from a cross bar 50. The cross bar 50 is provided at its opposite ends with flanges 51 and 52 which are apertured to receive bolts 53 and 54 for securing the cross bar to outturned flanges at the upper end of the castings at the ends of the opposite side walls.

40 The cross bar 50 not only supports the bearing arms 49 and 48 for the conveyer supporting shafts 45 but also serve to secure the upper ends of the side walls in properly spaced relation. A filler member 15 is 45 bolted to the lower flanges of the opposite side walls and to the castings at the ends thereof, as indicated clearly in Figures 3 and 6 of the drawings.

50 The number of sections of the conveyer box will vary with the number of gins to be supplied, but each section following the first is substantially the same as every other section and is provided with the flanged castings by means of which each section is detachably connected to the adjacent section or sections.

55 Each filler member 15 has a flange turned inwardly from the lower edge of the wall 19, and this flange 55 is provided with suitable apertures by means of which the upper flanged edges 56 and 57 of the hoppers H, H1, etc., are secured to the distributor conveyer box.

60 Each hopper used with this invention comprises a casing 58 having the flanges 56 and

57 formed on the upper edges thereof. The casing 58 is substantially rectangular in cross section and has the lower part 59 thereof laterally extended to provide a valve chamber 60. Shafts 61 and 62 are journaled in said chamber and are provided with valve plates 63 and 64 respectively. These plates are adapted to be swung from the closing position shown in full lines in Figure 12 to an open position shown by the dotted lines in 75 the same figure.

70 As will be apparent from Figure 12 of the drawings, when the plates 63 and 64 are in the dotted line position the cotton falls freely through the hopper to the gin feeder and without being in any way obstructed. By this construction the cotton is delivered on to the center of the feeder drum thereby allowing a great spread of the cotton as it is carried over the screen back of the feeder and thus permits better cleaning and provides little opportunity for choking the feeder.

75 The shafts 61 and 62 extend through one end of the hopper casing. The shaft 61 has a crank arm 65 secured thereto by a set screw 66. The shaft 62 has a crank arm 67 secured thereto by a set screw 68; and the free ends of the crank arms 65 and 67 are pivotally connected to the opposite ends of a link 69. An operating lever 70 is also secured to the shaft 62 and serves to rotate the shaft 62 in order to transmit the rotation thereof through the crank arm 65 and 67 and intermediate link 69 to the shaft 61. The linkage is so designed and arranged on the shafts 61 and 62 that the two valve plates 63 and 64 open and close together. The weight of the valve plates is such that they 100 normally hang in the open position shown by dotted lines in Figure 12. In other words, the weight of the valve plate is sufficient to overbalance the operating linkage and the lever 70 connected thereto.

105 In the operation of this system it is frequently desirable to open the valve plates 63 and 64 at various degrees in order to regulate the flow of cotton through the hoppers to the feeder drums. The control of this valve mechanism is effected by a handle 71 which has one end pivotally connected to the free end of the lever 70, and has its other end formed as a hand grip 72 adapted to be engaged with any of the hoops 73, 74, 75, and 76. These hoops are located at various distances apart on a plate 77 suitably secured to the casing of the gins 78.

110 It should be noted here that the valve plates 63 and 64 are sufficiently heavy to overbalance the operating linkage connected to the shafts 61 and 62 and also the handle 71 connected to said linkage. This means that when the hand grip 72 is disengaged from all of the hoops 73, 74, 75 and 76, the valves remain 115 in the open position indicated by dotted lines 120 125 130

in Figure 12, and the linkage assumes the position indicated by dotted lines in Figure 10.

By variously adjusting the control valves of the hoppers leading to a battery of gins, the density of the bed of cotton in the space above the feeder rollers is varied and the flow of cotton from the feeder is varied accordingly. This aids materially in having all the gins complete the ginning of a certain bale of cotton more evenly, and prevents the necessity of waiting until the first gin has finished—and so on down the line.

It will also be apparent that the various valve mechanisms of the hoppers leading to a battery of gins can be relatively regulated so that the cotton feeds at the same rate through all the feeders, and so that overflow may be practically eliminated. It is obvious that the greatest density of the cotton in the conveyer mechanism exists above the first hopper, and that this density decreases as the cotton is conveyed toward the overflow end of the system. If the valves be opened wider as they approach the overflow end it is evident that they may be positioned so that the rate of flow through the various hoppers is substantially the same.

It will also be apparent that by adjusting the openings of the several hopper valves in accordance with the speed of rotation of the conveyer screws, the overflow can be practically eliminated, since the valves can be opened sufficiently to take care of all the cotton passing through the conveyer box. This practical elimination of the overflow has a decided advantage over the prior system, because it provides less cotton to be handled through the cleaning equipment and avoids the danger of machining the cotton, which causes the roping of the cotton and is injurious to the staple.

While I have shown the system as embodied in specific apparatus, it must be understood that the invention is not to be limited to the particular form of the apparatus shown, nor in any other way except as required by the scope of the claims appended hereto.

What I claim is:

1. A cotton distributor comprising a trough having the sides thereof bent from sheet metal to form a plurality of plane faces arranged at an angle to each other, spaced apart filler members detachably connecting the opposite sides to each other, a bearing plate connected to one of said filler pieces and to the adjacent ends of a pair of sides, a cross bar connecting the upper edges of the other ends of said sides, a pair of arms depending from said cross bar and having journal bearings formed in the ends thereof, a pair of screw conveyers journaled in said bearing plate and bearings, and means for rotating said screw conveyers in opposite directions.

2. A cotton distributor comprising a trough having the opposite sides thereof bent from sheet metal to form a plurality of plane faces arranged at an angle to each other, spaced apart filler members detachably connecting the ends of the opposite sides to each other, a bearing plate detachably connected to one of said filler pieces and to the adjacent ends of a pair of sides, a cross bar connecting the upper edges of the other ends of said sides, a pair of arms depending from said cross bar and having journal bearings formed in the ends thereof, a pair of screw conveyers journaled in said plate and bearings, means for rotating said screw conveyers in opposite directions, and means for controlling the rate of flow of cotton from said conveyer box through said hoppers.

3. A cotton distributor comprising a trough having a bearing plate closing one end thereof, a cross bar secured to the opposite end of said trough and having a pair of arms depending therefrom, a pair of screw conveyers journaled in said bearing plate and in the ends of said arms, a pair of filler pieces spaced apart to form the bottom of said trough and the entrance to a hopper, a hopper secured to said filler pieces, means for rotating said conveyers in opposite directions, and means in said hopper for varying the rate of flow of cotton therethrough.

4. A cotton conveying system for distributing cotton to a battery of gins, comprising a conveyer box built up of sections detachably connected to each other and extending over said gins, each gin having a separate section for controlling the feed of cotton thereto, each section including a pair of sides bent from sheet metal to form a plurality of plane faces arranged at an angle to each other, a casting suitably secured to the opposite ends of each side, a closure plate detachably connected to the castings at the adjacent ends of one pair of sides, a cross bar detachably connected to the castings at the other ends of said pair of sides and having bearing arms depending therefrom, spaced apart filler members secured to the lower edges of said sides at the opposite ends thereof, and a pair of screw conveyers journaled in said closure plate and in the lower ends of said bearing arms.

5. A cotton conveying system for distributing cotton to a battery of gins, comprising a conveyer box built up of sections detachably connected to each other and extending over said gins, each gin having a separate section for controlling the feed of cotton thereto, each section including a pair of sides bent from sheet metal to form a plurality of plane faces arranged at an angle to each other, and having their top and bottom edges provided with angle bars, spaced apart filler members secured to the angle bars at the lower edges of said pair of sides, a cover plate connecting the

angle bars at the upper edges of said pair of sides and forming the top of said box, castings having flanges extending perpendicular to the faces of said sides and suitably secured to opposite ends thereof, a closure plate secured to the castings at one end of said pair of sides, a bearing member secured to the castings at the other end of said pair of sides, and a pair of spiral screw conveyers journaled in said plate and bearing member.

In testimony whereof I hereby affix my signature.

JEFFREY J. WALLACE.
